CLAIM

The ornamental design for a drawer unit, as shown and described.

DESCRIPTION

FIG. 1 is a perspective view of a drawer unit showing my new design;

FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective top view of the drawer unit showing an inner container sliding out of a housing; and,

FIG. 10 is an exploded perspective view of the drawer unit with panels in a disassembled state.

Brokens lines illustrate environment elements and/or portions of the drawer unit that form no part of the claimed design.

1 Claim, 8 Drawing Sheets(56)
